UNITED STATES PATENT OFFICE.

JESSE S. TEED, OF WALTON, NEW YORK.

WATER-MOTOR.

SPECIFICATION forming part of Letters Patent No. 429,487, dated June 3, 1890.

Application filed July 18, 1889. Serial No. 317,938. (Model.)

To all whom it may concern:

Be it known that I, JESSE S. TEED, a citizen of the United States, residing at Walton, in the county of Delaware and State of New York, 5 have invented certain new and useful Improvements in Water-Motors; and I do declare the following to be a full, clear, and exact description of the invention, such as will enable others skilled in the art to which it applies to make and use the same, reference being had to the accompanying drawings, and to the letters of reference marked thereon, which form a part of this specification.

This invention relates to water-motors that 15 are operated by the impact of a jet against buckets that are arranged in a circle about and connected with a shaft from which the power is taken.

The object of the invention is to discharge 20 the water wholly and entirely to one side of the wheel at a tangent and to hold the jet in contact with the bucket until the jet is wholly reversed and has spent its energy.

A further object is the construction of a 25 case for the wheel in which the bottom section can be removed to observe the position of the jet relative to the buckets, and in which the size of the jet can be readily adjusted to the head of water and the amount of work to 30 be performed.

The improvement consists of the novel features which will be hereinafter more fully described and claimed, and which are shown in the annexed drawings, in which—

35 Figure 1 is a vertical longitudinal section of a motor embodying my invention. Fig. 2 is a cross-section on the line $x-x$ of Fig. 1. Fig. 3 is a cross-section of the case on the line $y-y$ of Fig. 1, showing the gate on an enlarged scale. Fig. 4 is a detail perspective view of the gate. Fig. 5 is a front view of the bucket. Fig. 6 is a top plan view of the bucket.

The case is composed of the sides A and 45 A', the ends B and B', the bottom C, and the top D. The top D and the bottom C are bolted to the upper and the lower edges of the said sides and ends, respectively, substantially as shown. That portion of the bottom C opposite the wheel E slants and terminates at its 50 lowest end in the discharge-spout e.

The jet-opening b in the end B is closed by the gate F, which is vertically adjustable to regulate the size of the jet. The gate is held to the end B by the screws f', which pass 55 through the openings f therein. The reciprocating valve G, secured to the gate F and working in the opening b, prevents the water rising in said opening above the lower edge of gate F. This valve has recesses in its 60 sides, in which packing g is placed to form a close joint between the valve and the rear of the opening b, closed by a plate H. The valve, working between the plate H and gate F, is compelled to move without binding. The 65 stem h is grooved near the lower end, and the lugs d on the back of the gate embrace the groove and form a connection between the gate and the stem, so that the gate will be moved vertically with the stem when the latter is adjusted vertically. 70

The gate F is placed between end wall B and a partition or wall B², which has opening b², through which the water passes from the water space or chest comprised between the 75 said walls B and B². This opening b² is sufficiently large to permit free access to the wheel when end B is removed, and is closed by plate B', in which is formed opening b', of proper size and required height. The position of opening b' controls the relation of the jet to the buckets of the wheel. The wheel E is mounted on the shaft I, which is journaled in the bearings J and J', the bearing J' being supported on bracket j. The buckets 80 K, which are paraboliform, have one-half of the upper or outer side cut away and the edge of the remaining half k turned in and gradually thickened from the outer end toward the bottom of the bucket, where it vanishes or merges into the curved form of the bucket. The bucket is disposed relative to the jet so that the latter will strike the bottom of the bucket near the open side k' at k², 85 from which point the water will curve toward the closed side k³ of the bucket and leave the bucket at a tangent to the periphery of the wheel, as most clearly indicated by the lines in Fig. 5; hence it will be seen that the water leaves on one side of the wheel, thereby 90 not cushioning or detracting from the force of the jet. 95

Having described my invention, what I claim, and desire to secure by Letters Patent, is—

1. In a water-wheel, the combination, with the case having a jet-opening, of the gate for closing the opening and the valve having packing in its sides carried by the gate and working in the said jet-opening, substantially as described.
2. The combination, with the water-wheel case having a jet-opening *g*, of the gate *F*, having slots *f*, the screws *f'*, the plate *H*, and the valve *G*, carried by the gate and having its sides packed, substantially as and for the purposes specified.
3. The herein shown and described paraboliform bucket, having one-half of its exterior or outer side removed, substantially as described.

4. The hereinbefore-specified paraboliform bucket, having one half of its exterior side removed and having the edge of the other half turned in, substantially as and for the purposes described.

5. The herein shown and described paraboliform bucket, having one half of its outer side removed and having the edge of the other half turned in and gradually thickened from its outer end to the bottom of the bucket, where it vanishes, substantially as set forth.

In testimony whereof I affix my signature in presence of two witnesses.

JESSE S. TEED.
